SHOULDER PAD

Israel Kantor, New York, N. Y.

Application March 21, 1947, Serial No. 736,305

7 Claims. (Cl. 2—268)

1

This invention relates to shoulder pads.

It is an object of the invention to provide a shoulder pad having an arched contour which is obtained in a simple manner and at a low cost.

It is another object of the invention to provide an arched shoulder pad which for the most part is of standard construction and varies therefrom in only one simple respect to obtain the desired arched shape.

It is a further object of the invention to provide an arched shoulder pad in which the arched contour is imparted by a detachable element so that this element can be temporarily removed when the garment is cleaned.

It is an additional object of the invention to provide an arched shoulder pad of such construction that, even if the arching element is left in the pad during cleaning, the pad will retain its curved contour.

It is still another object of the invention to provide a shoulder pad of the character described which comprises relatively few and simple parts, is inexpensive to manufacture, easy to use and highly efficient in operation.

Other objects of the invention will in part be obvious and in part hereinafter pointed out.

The invention accordingly consists in the features of construction, combinations of elements, and arrangements of parts which will be exemplified in the constructions hereinafter described and of which the scope of application will be indicated in the appended claims.

In the accompanying drawings, in which are shown various possible embodiments of the invention,

Fig. 1 is a perspective view of a female figure wearing a dress in which is incorporated a shoulder pad embodying the present invention;

Fig. 2 is an enlarged sectional view taken substantially along the line 2—2 of Fig. 1 and showing the pad as it appears when observed edge foremost;

Fig. 3 is a longitudinal sectional view through the pad, the same being taken substantially along the line 3—3 of Fig. 2;

Fig. 4 is a developed view of the pad;

Fig. 5 is a transverse sectional view through the pad with the arching element removed, the same being taken substantially along the line 5—5 of Fig. 4;

Fig. 6 is a plan view of the arching element;

Fig. 7 is a view similar to Fig. 4 of a shoulder pad embodying a modified form of the invention;

Fig. 8 is a longitudinal sectional view taken through the shoulder pad shown in Fig. 7;

2

Fig. 9 is a view similar to Fig. 4 of a shoulder pad embodying another modified form of the invention;

Fig. 10 is a longitudinal sectional view taken through the shoulder pad shown in Fig. 9;

Fig. 11 is a plan view of the arching element employed in the shoulder pad of Fig. 9; and

Fig. 12 is a fragmentary sectional view illustrating the manner in which an end of the arching element is secured in the shoulder pad of Fig. 9.

In general, the several objects of the invention are achieved by providing a conventional shoulder pad comprising by way of example one or more layers of a light bulky material such as cotton batting or felt fibers which is covered with a fabric or similar substance known to the art as a "casing." To this conventional pad there is added a self-form-maintaining, preferably resilient, member which is slender, elongated and simply curved, i. e. has no points of inflection. Means also is included, either on said member or the shoulder pad, to hold the member to the pad along a zone which runs parallel to the shoulder edge of the pad and, optionally, is located near said edge. The simply curved member thus will impart the desired arched shape to said edge of the pad and also will cause the balance of the pad to assume a similar curved profile.

Referring now in detail to the drawings, the female figure shown in Fig. 1 is wearing a dress whose shoulders are built up with the aid of shoulder pads constructed in accordance with the invention. Each of said pads comprises a sheeted deformable mass 12 of loosely interlocked fibers,

e. g. a cotton or wool bat, such as is customarily employed in the fabrication of shoulder pads. This mass is shaped to the desired outline, (usually semi-circular or triangular) and the mass is disposed within a protective covering, for instance between facings or inside a casing 14 made of cloth. By way of example, said casing is shown herein as consisting of a single fabric sheet which is folded over the wide or shoulder edge of the mass 12 and whose cut edges are registered just outside of the rearwardly converging edges of the mass. Said edges are held together by lines 15 of stitching.

One surface of the casing is formed with an elongated transversely extending pocket 16 arranged to detachably receive therein an elongated, simply curved, resilient member 18 of self-form-maintaining material. This member may be made from any one of the well known synthetic plastics or, alternatively, may comprise a sheet

metal strip or wire, e. g. of stainless steel or phosphor bronze, of suitable thickness, for example 16 gauge. Said member is slender and arched to the shape which is desired to have the shoulder pad assume.

The pocket 16 can be formed by securing the longitudinal edges of a transversely extending tape to a surface of the casing adjacent the shoulder edge thereof, or, as illustrated, said pocket may be provided by doubling back a transversely extending portion of the fabric at one surface of the casing, this doubled back portion being held in place by two spaced rows of stitching 20, 22. One of these rows, if desired, may extend through the shoulder pad, i. e. through the mass 12, and the other surface of the casing. The ends of the pocket are defined by the inner rows of stitching 15.

The member 18 may be permanently held in place, in which case it is disposed within the pocket before the rows of stitching 20, 22 are applied. Alternatively, and as shown, the member may be detachably held in place, and for this purpose the pocket 16 is left open adjacent one or both ends thereof, as by terminating one or both ends of the row of stitching 20 short of the ends of said pocket to provide a gap 19. This enables the arching member to be inserted in the pocket from either side of the casing and to be withdrawn when necessary, as for instance when the pad or dress is to be cleaned.

In Figs. 7 and 8 there is illustrated a shoulder pad 30 embodying a modified form of the invention. This pad is essentially similar to the pad 10 and differs therefrom only in the formation of the pocket for receiving the arching member 18. The pocket 32 in which said member is held is, like the pocket 16, formed by doubling back a transversely extending portion of the fabric on one side of the shoulder pad casing. However, only one transverse row of stitching 34 extends across the shoulder pad to hold the base of this doubled back portion in place. The other transverse row of stitching at the tip of the doubled back portion, which in the pad 10 comprises the row 20, is omitted and in lieu thereof short transverse lines of stitching 36, 38 are employed, these lines being disposed adjacent the inner rows 15 of stitching at the converging edges of the pad and being spaced from and parallel to the row of stitching 34.

When it is desired to insert the arching member in the pocket 32, one end of the member is introduced into the space between the row of stitching 34 and a short line of stitches, e. g. the line 36. Then the other end of the member is introduced between the row of stitching 34 and the other short line of stitching 38. The distance between the two short lines of stitching 36, 38 is less than the length of the arching member 18 so that when said member once is in place it can not be removed except intentionally. In order to simplify insertion of the arching member elements, the distance from the inner row 15 of stitching at either end of the pocket to the remote of the short lines of stitching is greater than the length of said arching member.

Another means for detachably securing an arching member to a shoulder pad is illustrated in the pad 40 shown in Figs. 9-12. In this embodiment of the invention said pad is entirely conventional and is not even provided with a pocket to receive and hold an arching member. Said pad has associated with it an arching member 42 of the same general configuration and con-

struction as the members 18 already described. However, the arching member 42 additionally includes a means carried by said member for detachably securing the same to the pad. Said means, as illustrated herein, includes wires 44, 46 fixed to both ends of the member and extending therefrom. Said wire is of self-form-maintaining but manually deformable metal, as for instance soft steel. Optionally the tips of the wire may be pointed.

To secure the arching member 42 to the shoulder pad 40, the two wires 44, 46 are thrust through the pad and their tips curled back into the pad as best seen in Figs. 10 and 12. The spots 15 on the pad at which the wires are inserted may be marked on the pad or can be determined in a few moments by trial and error. Said spots are spaced apart a distance approximately equal to the length of the arching member exclusive 20 of the wires 44, 46. At the time the wires are thrust into the pad, the arching member is held with its concave side facing the pad. Subsequently said member is swung 180° into its operating position before the wires are curled back.

It thus will be seen that there are provided shoulder pads which achieve the several objects of the invention and are well adapted to meet the conditions of practical use.

As various possible embodiments might be 30 made of the above invention and as various changes might be made in the embodiments above set forth, it is to be understood that all matter herein described or shown in the accompanying drawings is to be interpreted as illustrative and not in a limiting sense.

Having thus described the invention, there is described as new and desired to be secured as Letters Patent:

1. A shoulder pad including a layer of light, 40 bulky deformable material, a casing of fabric covering said layer, a self-form-maintaining, elongated, slender, simply curved, resilient arching member, and a pocket on said casing which extends transversely across the same near the shoulder edge, said member being disposed in said pocket, said pocket having an opening therein through which the arching member is insertable and removable.

2. A shoulder pad including a layer of light, 50 bulky deformable material, a casing of fabric covering said layer, a self-form-maintaining, elongated, slender, simply curved, resilient arching member, and a pocket on said casing which extends transversely across the same near the shoulder edge, said member being disposed in said pocket, said pocket having an opening adjacent an end thereof through which the arching member is receivable and removable.

3. A shoulder pad including a layer of light, 60 bulky deformable material, a casing of fabric covering said layer, a self-form-maintaining, elongated, slender, simply curved, resilient arching member, and a pocket on said casing which extends transversely across the same near the shoulder edge, said member being disposed in said pocket, said pocket having an opening in a longitudinal side edge adjacent an end thereof through which opening the arching member is receivable and removable.

4. A shoulder pad including a layer of light, 70 bulky deformable material, a casing of fabric covering said layer, a self-form-maintaining, elongated, slender, simply curved, resilient arching member, and a pocket on said casing which extends transversely across the same near the

shoulder edge, said member being disposed in said pocket, said pocket having a long central opening along one side thereof through which said arching member is receivable and removable, said opening being shorter than the length of the arching member.

5. A shoulder pad including a layer of light, bulky deformable material, a casing of fabric covering said layer, a self-form-maintaining, elongated, slender, simply curved, resilient arching member, and a pocket on said casing which extends transversely across the same near the shoulder edge, said member being disposed in said pocket, said pocket having a long central opening along one side thereof through which said arching member is receivable and removable, said opening being shorter than the length of the arching member, the distance from one end of the pocket to the opposite side of the opening being greater than the length of the arching member.

6. A shoulder pad including a layer of light, bulky deformable material, a protective covering for said layer, a self-form-maintaining, elongated, slender, simply curved arching member, and means associated with said member and adapted to cooperate with said covering to de-

tachably hold said member against said pad in a position extending transversely across the pad.

7. A shoulder pad including a layer of light, bulky deformable material, a protective covering for said layer, a self-form-maintaining, elongated, slender, simply curved arching member, and means associated with said member and adapted to cooperate with said covering to detachably hold said member against said pad in a position extending transversely across the pad, said last named means comprising manually deformable thin elements such as wires extending from the ends of said member.
